UNITED STATES PATENT OFFICE.

WILLIAM C. CLARKE, OF NEW YORK, N. Y.

APPARATUS FOR GENERATING GAS.

SPECIFICATION forming part of Letters Patent No. 552,100, dated December 31, 1895.

Application filed March 21, 1895. Serial No. 542,585. (No model.)

To all whom it may concern:

Be it known that I, WILLIAM C. CLARKE, a citizen of the United States, residing in the city of New York, in the county and State of New York, have invented a new and Improved Apparatus for Generating and Supplying Illuminating-Gas, of which the following is a specification.

My invention applies generally to the use of acetylene-gas as an illuminating-gas, and is more especially intended to be used in connection with the production of such gas by the mutual decomposition of water and an acetylide or carbide, such as the material known, as "carbide of calcium." As is well known this material, which may be taken as a type of others of kindred composition and the same nature, when brought in contact with water is decomposed together with the water, giving off as one of the elements of decomposition acetylene-gas. This gas burns with a flame of great brilliance and luminosity; and the object of my improvements is to provide a safe, simple and economical means and method for its production and application for illuminating purposes, and particularly in connection with that class of small gas-plants such as are used for local purposes—as, for example, in the lighting of country houses. To this end I provide a gas-holder having in its upper surface an opening closed by a removable cover, which when in place is made gas-tight, preferably by a liquid seal. To the cover is attached a cylinder or generating-chamber, which, when the cover is in place, projects down into the gas-holder, and when the holder does not contain gas into the water with which the lower part of the holder is filled. The holder is connected by a pipe, which projects upward within it to a point above the level of the water which it contains, with the ordinary delivery-pipe to the burners. In using the apparatus the cover is removed from the opening in the gas-holder and the generating-chamber is charged with carbide of calcium, which is preferably contained in a perforated cartridge adapted for the purpose. On placing the cover in position, the generating-chamber is immersed in the water within the holder, which immediately enters the generating-chamber through openings provided for the purpose and coming in con-

tact with the material in the chamber acetylene-gas is developed. The holder is lifted by the gas and gradually falls as the gas is used at the burners. In case the carbide of calcium is not fully decomposed by its first contact with the water the generating-chamber is again immersed in the water when the gas-holder has fallen to the proper point, and the operation is repeated until the gas-forming capacity of the material is exhausted. When the gas in the holder is all used the cover is removed, the generating-chamber cleaned out and recharged, and the operation is repeated as before.

In order to provide for a continuous supply, while recharging the gas-holder, I provide a series of two or more such holders, which are all connected to the common riser or feed-pipe of the burner system. The several holders of the series being filled with gas, a downward pressure is applied to one of the holders, greater than the others are subjected to, as by applying a weight to such holder. The holder thus subjected to pressure leads the others in the delivery of gas, and is emptied of its contents through the consumption of the gas to the burners, while the others still remain ready for operation. The pressure is then shifted to another holder of the series, while the first is recharged and again filled with gas ready for operation. In this manner the several holders of the series are successively exhausted and recharged as required without any interruption in the delivery of gas.

The apparatus is illustrated in the accompanying drawing, which shows an elevation of a series of gas-holders, one of the series being in section, to show its internal construction.

A indicates the external shell of the holder within which is a bell or holder proper B. The shell A is kept filled with water to such a point that when the holder B contains no gas its top will nearly rest on the surface of the water. From a point within the holder B, above the surface of the water, a pipe C connects with the main supply-pipe D, leading to the burners. In the top of the holder B is an opening E, closed with a cover F, which is supplied with a liquid seal G, of water, glycerine, or other suitable liquid. The weight

of the cover F and the depth of the liquid seal are such that the seal will not be broken when the holder is raised by the pressure of gas within it. To the cover F is removably attached a vessel or generating-chamber H, which, when the cover F is in place, projects downward into the holder B, and is wholly or partially immersed in the water within the holder when the holder is down. 5 The generating-chamber H is provided with perforations h h, so that when the chamber is in place the water in the holder can come in contact with its contents.

In using the apparatus the cover F is removed and a charge of material which by contact with water will produce acetylene-gas, such as carbide of calcium, is placed in the generating-chamber H. The material is preferably inclosed within a perforated cartridge 20 or holder, as I, so that the residue of decomposition may be readily removed from the chamber H, and will not escape into and accumulate in the holder B. The cover F is then placed in position on the holder, the generating-chamber H, by the same act, being lowered into the holder and immersed in the water therein. The opening E is closed by means of the liquid seal as the cover F goes into place, so that none of the gas, which 30 begins to be developed as soon as the water in the holder comes in contact with the contents of the generating-chamber, can escape. As the gas is generated, the holder is lifted, raising the generating-chamber out of the water, and the gas is ready for use at the burners. 35 In the same manner the other holders of the series are charged with gas, and discharge their contents through the pipes c'', &c.

40 Ordinarily I prefer to charge the generating-chamber H with such a quantity of the gas-forming material that it will be fully decomposed upon its first immersion in the water and will provide only sufficient gas to fill the 45 holder at a low pressure. The generating-chamber will, however, be again immersed in the water as the holder descends by reason of the consumption of the gas, and in case any of the material remains undecomposed in the 50 first instance it will, upon the subsequent immersions be fully acted upon.

In order to provide for the recharging of the 55 holders with gas without interfering with the delivery of gas at the burners, I proceed as follows: Having charged two or more holders with gas, I then apply a slight pressure to one of such holders, as the holder B, which may be done in any convenient manner, as by applying a weight or weights W thereto. The

pressure thus applied gives such holder the 60 lead in the delivery of gas, which is drawn therefrom for use at the burners to the exclusion of the other holder or holders, which retain their supply of gas ready for delivery. When the gas is exhausted from the holder 65 under pressure, such holder is cut off from connection with the other holders by means of a valve V in the pipe C, and the pressure is transferred to another holder in the series, which will then begin to deliver gas, while the 70 exhausted holder is recharged and again made ready for use. In this manner a constant supply of gas is kept on hand, and the several holders can be recharged without interrupting the flow of gas to the burners. 75

Other means of applying pressure to the holders than that shown may be employed without departing from the spirit of my invention, and I may also employ other means of making tight the opening in the top of the 80 holder than a liquid seal, though I prefer this, since by means of it the opening is closed against the escape of gas, even before the cover is fully in place on the opening.

By means of my invention I am able to produce a continuous supply of illuminating-gas in a safe and simple manner and to recharge the apparatus from time to time without causing the escape of any material quantity of gas, advantages which will be readily apparent to 90 those skilled in the art.

What I claim as new, and desire to secure by Letters Patent, is—

1. An apparatus for generating and supplying gas consisting of an expansible gas holder having an opening in the top thereof, a removable cover for such opening and a gas generating chamber attached to such cover and removable therewith and, when the cover is in place, projecting downward into the gas holder, substantially as and for the purposes set forth.

2. In an apparatus for generating gas, the combination of an expansible gas holder, an opening in the top of such holder and a removable cover therefor having a liquid seal, and a generating chamber attached to the cover and removable therewith and projecting downward into the holder when the cover is in place, substantially as and for the purposes set forth.

In testimony whereof I have hereunto subscribed my name this 20th day of March, A. D. 1895.

WILLIAM C. CLARKE.
